UNITED STATES PATENT OFFICE.

PIETER JOOSTING, OF Utrecht, NETHERLANDS.

LIFT BRIDGE.

1,422,717.

Specification of Letters Patent.

Patented July 11, 1922.

Application filed March 7, 1921. Serial No. 450,165.

To all whom it may concern:

Be it known that I, PIETER JOOSTING, a subject of the Queen of the Netherlands, and residing at Utrecht, Netherlands, have invented certain new and useful Improvements in Lift Bridges, of which the following is a specification.

My invention relates to lift bridges adapted to be raised and lowered by means of ropes or the like operated by one or more stationary drums, and has for its object to provide simple means for moving the span, a further object being means for preventing the movable span from going out of square with its guide towers or columns. Still another object of the invention and one which results from the said improved means is lightness and simplicity in the structure of both movable span and fixed parts.

It has been proposed to mount the span hoisting and/or lowering machinery on the moving lifting span itself, but this system, which has been disclosed in U. S. specification for Patent No. 932,359, has the disadvantage that the weight of the lifting span is considerably increased. Other disadvantageous features are that transmission of electric energy to the machinery on the span necessitates a trolley system, that telephonic communication between the movable engine room and the bank of the river or canal, which is often unavoidable, is difficult to realize, that the bridge-tender cannot overlook the ship way sufficiently from the lifted span and, in railway bridges, that the operation of the safety signalling system on the line by the bridge-tender requires complicated arrangements.

In other known systems the towers are at their tops interconnected by means of a fixed span or strut for supporting ropes extending from one tower to the other, and receiving the horizontal pull of said ropes on the tops of the towers.

According to the present invention the movable span is adapted to be lifted by one or more ropes or other flexible pulling means each passing from the stationary drum over a sheave or other guiding means at the top of the adjacent column, thence over a sheave at one end of the span, thence to a sheave

at the other end of the span, and thence to a fixed point at the top of the opposite column to which it is secured.

In case the span is counterbalanced by weights in the usual way one or more lowering ropes or the like are to be used, each passing from the stationary drum over a sheave at the foot or in the lower part of the adjacent column, thence over a sheave at one end of the span, thence over a sheave at the other end of the span, and thence to a fixed point at the foot or in the lower part of the opposite column to which it is secured.

Owing to differences in the effect of friction in the sheaves at both ends of the span the latter might run out of square when being raised or lowered. Therefore I may use guide rollers engaging vertical rails on the columns to keep the span in a horizontal position.

I prefer, however, to use instead of guide rollers two guide ropes, or two sets of guide ropes or the like, the one running approximately in the form of a Z from a fixed point at the top of one column over sheaves of the span to a fixed point at the foot of the other column, the other rope or set extending oppositely from the top of the other column over sheaves of the span to a fixed point at the foot of the first named column, in such a manner that the ropes or the like in the form of a Z coact to ensure parallelism of the movement of the span.

The invention may be fully understood from the accompanying drawing which diagrammatically shows a lift bridge and the raising and lowering device therefore.

Figure 1 is a side elevation of the bridge showing the span lowered in full lines and elevated in dotted lines.

Figures 2 to 5 are diagrams of means for moving and guiding the span.

Figures 6 to 8 are diagrams of other means for preventing the lifting span from going out of square with the towers.

The counterbalanced span 6 is adapted to be lifted between the fixed columns 7 and 8, the first of which is provided with the house 9 containing the lifting and lowering machinery. This house may, of course, also

be placed under or in the neighbourhood of the column.

In Figure 2 the lifting drum is designated by 11. The lifting rope 12, which of course as well as the drum is suitably duplicated so that one rope or set of ropes runs at each side of the span, passes over a sheave 13 near the top of column 7, thence over a sheave 14 in the span, a number of sustaining rollers 15 in the span 6, a sheave 16 in the span and is secured to a fixed point 17 near the top of the column 8.

The lowering rope or set of ropes 20 are shown in Figure 3. From the lowering drum 19, which may be fixed on the same shaft as the lifting drum 11, or may be combined with the latter, the rope 20 passes over a sheave 21 at the foot of the column 7, thence over a sheave 22 at one end of the span 6, over a number of supporting rollers 15^a, a sheave 23 at the other end of the span to a fixed point 24 at the foot of the tower 8.

Fig. 4 shows one of the guide ropes or sets of guide ropes 25 extending in the form of a Z from a fixed point 26 near the top of column 7 over sheaves 27 and 28 and a number of supporting rollers 15^b in the span to a fixed point 29 at the foot of tower 8.

30 A similar guide rope 30 is shown in Fig. 5. It extends from a fixed point 31 near the top of the column 8 over sheaves 32 and 33 and a number of sustaining rollers 15^c in the span to a fixed point 34 at the foot of tower 7.

40 All ropes may be provided with suitable turn-buckles or spanners permitting to eliminate slack therein and to adjust the span so that the latter will be square with the vertical sides of the columns.

The guiding mechanism as diagrammatically shown in Figures 4 and 5 may be replaced by any other suitable or approved means. Figure 6 shows the lifting span 6 provided near each of its four corners with a set of two anti-friction rollers 35 and 36 suitably spaced apart vertically, each set engaging a vertical rail 37 secured to the towers.

50 According to Figure 7, the lifting span is provided at each end with a horizontal shaft 38 at right angles to the longitudinal axis of the span and supported in suitable bearings, said shaft carrying two gears 39 meshing with vertical racks 40 on the towers. The shafts 38 at both ends are coupled by mitre gearing so as to always rotate at equal angular speeds but in opposite directions.

60 Figure 8 shows the span 6 as having a horizontal drum 41 at each end, ropes 42 running over each of these drums being fixed at top and foot of the adjacent tower, both drums being coupled by mitre gearing so as to always revolve at equal angular speeds.

Having thus described my invention, what I claim as new therein and desire to secure by Letters Patent is:—

1. In a lift bridge, the combination with stationary towers, of a span adapted for vertical travel between said towers, a fixed lifting and lowering machinery, flexible pulling means extending from said machinery over guiding means at the upper part of the tower adjacent to said machinery and thence over guides in the span to a fixed point in the upper part of the other tower, and means adapted to prevent the span from going out of square with the towers.

2. In a lift bridge, the combination with stationary towers, of a counterbalanced span adapted for vertical travel between said towers, a fixed lifting and lowering machinery, flexible pulling means extending from said machinery over guiding means at the upper part of the tower adjacent to said machinery and over guides in the span to a fixed point in the upper part of the other tower, another flexible pulling means extending from said machinery over guiding means at the foot of the tower adjacent to said machinery and thence over guides in the span to a fixed point at the foot of the other tower, and means adapted to prevent the span from going out of square with the towers.

3. In a lift bridge, the combination with stationary towers, of a span adapted for vertical travel between said towers, a fixed lifting and lowering machinery, flexible pulling means extending from said machinery over guiding means at the upper part of the tower adjacent to said machinery and over guides in the span to a fixed point in the upper part of the other tower, and 105 Z-shaped flexible pulling means of which the one extends from a fixed point at the top of one tower over guides in the span to a fixed point at the foot of the other tower and the other extends from a fixed 110 point at the top of the other tower over guides in the span to a fixed point at the foot of the first mentioned tower.

4. In a lift bridge, the combination with stationary towers, of a counterbalanced span 115 adapted for vertical travel between said towers, a fixed lifting and lowering machinery, flexible pulling means extending from said machinery over guiding means at the upper part of the adjacent tower and 120 over guides in the span to a fixed point in the upper part of the other tower, flexible pulling means extending from said machinery over guiding means at the lower part of the adjacent tower, over guides in 125 the span to a fixed point in the lower part of the other tower, and Z-shaped flexible pulling means of which the one extends from a fixed point at the top of one tower over guides in the span to a fixed point at 130

the foot of the other tower and the other extends from a fixed point at the top of the other tower over guides in the span to a fixed point at the foot of the first mentioned tower.

5. In a lift bridge, the combination with stationary towers, of a span adapted for vertical travel between said towers, means for moving said span, and Z-shaped flexible

pulling means of which the one extends from 10 a fixed point at the top of one tower over guides in the span to a fixed point at the foot of the other tower and the other extends from a fixed point at the top of the other tower over guides in the span to a fixed 15 point at the foot of the first mentioned tower.

In testimony whereof I affix my signature.
PIETER JOOSTING.
